(57) **CLAIM**

The ornamental design for an electronic cigarette assembly, as shown and described.

DESCRIPTION

FIG. 1 is a perspective view of an electronic cigarette assembly where the atomizer component and the body component are shown in an assembled state of use; FIG. 2 is an exploded view of the electronic cigarette assembly shown in FIG. 1, with the atomizer component and the body component of the electronic cigarette assembly are shown in a separated state;

FIG. 3 is a front view thereof;

FIG. 4 is a rear view thereof;

FIG. 5 is a left view thereof;

FIG. 6 is a right view thereof;

FIG. 7 is a top view thereof;

FIG. 8 is a bottom view thereof;

FIG. 9 is a perspective view of the electronic cigarette assembly showing the atomizer component removed from the assembly in FIGS. 1–8 for clarity of disclosure;

FIG. 10 is a front view thereof;

FIG. 11 is a rear view thereof;

FIG. 12 is a left view thereof;

FIG. 13 is a right view thereof;

FIG. 14 is a top view thereof;

FIG. 15 is a bottom view thereof;

FIG. 16 is a perspective view of the electronic cigarette assembly showing the body component removed from the assembly shown in FIGS. 1–8 for clarity of disclosure;

FIG. 17 is a front view thereof;

FIG. 18 is a rear view thereof;

FIG. 19 is a left view thereof;

FIG. 20 is a right view thereof;

FIG. 21 is a top view thereof; and,

FIG. 22 is a bottom view thereof.

The broken line portions of the electronic cigarette assembly in FIGS. 1, 2, 7–16 and 19–22 represent unclaimed portions of the claimed design and form no part thereof.
